UNITED STATES PATENT OFFICE.

ALEXANDER MILLER, OF ALCBEMARLE, NORTH CAROLINA.

DUPLEX ENVELOP.

1,115,229.

Specification of Letters Patent. Patented Oct. 27, 1914.

Application filed March 10, 1914. Serial No. 823,697.

To all whom it may concern:

Be it known that I, ALEXANDER MILLER, a citizen of the United States, and a resident of Albemarle, in the county of Stanly and State of North Carolina, have made an Improvement in Duplex Envelops, of which the following is a specification.

My invention is an improvement in the small duplex or "twin" envelops designed 10 particularly for use in churches to receive offerings for different purposes.

The feature of novelty is the construction of the middle or connecting portion of the twin envelops.

15 In the accompanying drawing, Figure 1 is a perspective view of the twin envelops with the closing flaps extended or unclosed. Fig. 2 is a transverse section on the line 2—2 of Fig. 1. Fig. 3 is a plan view of the twin-envelop blank having its flaps gummed.

20 In Figs. 1 and 2, the numeral 1 indicates the bodies of the two envelops which are connected at their inner ends, as indicated at 1^a, each being provided with top, gummed, sealing flaps 2, which, in Fig. 1, are shown extended or open.

25 The lower half of the blank, as shown in Fig. 3, has folding end flaps 3 which are gummed on the outer side and thus adapted, when folded inward, to be sealed, as shown in Fig. 2.

30 A narrow open slot 4 extends, as shown in Fig. 1, between the narrow end connections 1^a of the two envelops 1—1, and this is pro-

duced by cutting out the blank on the lines 35 5, indicated in Fig. 3. By this means narrow flaps 6 are formed which are adapted to fold in opposite directions, and, being gummed as shown in Fig. 3, they may be sealed on the outer sides of the respective 40 receptacles or envelops 1—1 as shown in Fig. 2.

Thus, by the construction described, the two envelops 1 and 1 may be instantly and very easily separated or torn apart, when it is desired to collect and distribute offerings deposited therein; and, by the folding of the flaps 6 over the inner edges of the envelops, the capacity of the envelops is enlarged to a greater degree than would be 50 practicable if the flaps were dispensed with and the opposite gummed edges sealed together.

I claim:

The improved duplex envelop comprising 55 two receptacles arranged end to end and connected by narrow portions, at their upper and lower edges, the intervening central portion being provided with a transverse open slot and with flaps formed in cutting 60 said slot, the flaps being gummed and folded in opposite directions and lapped upon the adjacent edges of the envelop bodies, as described.

ALEXANDER MILLER.
